Patented July 9, 1912.

UNITED STATES PATENT OFFICE.

ALBERT P. ALBERT, OF NEW ORLEANS, LOUISIANA.

COTTON-PICKING APPARATUS.

1,031,902.

Specification of Letters Patent. Patented July 9, 1912.

Application filed January 8, 1908. Serial No. 409,885.

To all whom it may concern:

Be it known that I, ALBERT P. ALBERT, a citizen of the United States, residing at New Orleans, in the parish of Orleans and State 5 of Louisiana, have invented a certain new and useful Improvement in Cotton-Picking Apparatus, of which the following is a specification.

This invention relates, generally, to cotton 10 picking apparatus of the type in which air is used as a medium for removing the cotton from the boll and conveying it to the receptacle provided therefor preparatory to its conveyance to the gin, and it particularly 15 relates to an improvement in the nozzles or mouthpieces of the picking tubes of such apparatus.

The object of the invention is to provide a durable, effective, and inexpensive device for 20 loosening or dislodging the fiber from the boll to enable the current or air suction to draw it rapidly away from the boll, with the minimum quantity of trash, and through the tube to the receptacle, and it consists of the 25 parts and combinations of parts hereinafter described and claimed.

In the accompanying drawings, forming a part of this specification, Figure 1 is a longitudinal vertical section of my invention, showing parts of the conveying pipe 30 and the mouthpiece pipe broken away. Fig. 2 is an end view of the nozzle or mouthpiece. Fig. 3 is a vertical section on the line 3—3, Fig. 1. Fig. 4 is a detail vertical 35 section of the nozzle or mouthpiece showing a modification of the arrangement of the air inlets to casing.

Since the invention relates merely to the nozzle or mouthpiece and may be applied to 40 any machine or apparatus of the type above mentioned, it is not deemed necessary to illustrate any part of the machine or apparatus, proper, excepting a portion of the conveying tube in order to show the connection 45 between the parts.

Referring to the drawings A represents the cotton conveying pipe which leads from the coupling pipe B of the nozzle or mouthpiece casing C to the casing of the fan or 50 other means employed to create an air suction. The conveying pipe A is, as usual, flexible and the coupling pipe B is connected thereto in this instance by forcibly inserting the coupling pipe B, which may be 55 of metal or other suitable material, into the end of the pipe A, but any preferred means

for connecting and securing the pipes together may be employed. The nozzle casing C consists of the cylindrical body portion a having a tapering forward wall or end b, 60 and the reduced tubular end portion c. The opposite end of the casing C is open and a spider frame D is arranged and secured therein which supports a casing E, centrally within the casing C, which surrounds or 65 incloses the blades F spirally arranged on the picking tube or cylinder G. The casing E may be secured at its inner end to the spider by bolts or rivets or in any other preferred or convenient manner. The frame 70 D also supports the pipe B through the flange d on the latter. The forward end of the inner casing E is bent inward to form a flange e which serves to direct the incoming air directly against the sides of the 75 blades F and thereby impart rotary motion to the same.

The casings C and E are so spaced apart as to provide a circular passage between them for the incoming air which, in Fig. 1, 80 is shown as being drawn through the open rear end of the casing C and entering the forward end of the inner casing E, as indicated by arrows.

The picking tube or cylinder G is supported anti-frictionally at or near its rear and forward ends, a box for the balls g being formed by the shell bands f and h, the bands f being secured in an angle formed for the same in the pipe B and in the forward portion of the casing C, while the bands h are secured to the picking tube or cylinder G. The picking tube or cylinder G is formed with a series of openings i near its rear end through which the air is sucked, 85 or drawn by the suction creating mechanism, from the inner casing to the interior of the picking tube or cylinder G and through pipe B to the tube A. The picking tube or cylinder G extends into and beyond the reduced end c of the casing and carries a curved cam wheel H which is intended to actuate the spring metal finger J which is secured to reduced portion c of the casing C, once each 90 revolution of the picking tube or cylinder G. 95 As shown in Fig. 2, the end of the finger J is serrated or toothed. The end of the spring metal finger is gradually lifted or sprung back, as indicated in dotted lines, by the cam wheel and as the latter passes off 100 the finger, the latter drops or springs back 105 and its teeth enter the cotton and dislodge 110

any adhering fiber so that it may be readily drawn into the picking tube or cylinder G by the air which is sucked in to the said picking tube or cylinder through the openings i. The use of the cam and finger is not absolutely essential to the effective operation of the device but it is of assistance when the cotton for any reason adheres to the boll. Within the end of the picking tube or cylinder G is snugly fitted a short picking tube K so as to rotate with said picking tube or cylinder through contact therewith. The tube K is formed with an inclined continuous groove m into which a pin L secured to the picking tube or cylinder G extends in order to, at times, impart a reciprocating movement to said tube K. As above stated, the tube K rotates with the picking tube or cylinder and practically forms a part thereof but should the teeth n carried by the tube encounter an obstruction when presented to the cotton boll of a nature to overcome the frictional contact between the tube and the picking tube or cylinder, the pin L immediately engages the walls of the groove m and moves the tube longitudinally, back and forth, causing its teeth to move in and loosen the cotton in the boll and thus release the same and also release the teeth from the obstruction. Ordinarily the tube merely revolves with the picking tube or cylinder and its teeth act to loosen up and pick the cotton so that the current may readily draw the same away from the boll.

In Fig. 4 I show the casing C formed with perforations p at its forward end in order to admit the air at that point instead of at the rear end as shown in Fig. 1. In the use of the casing shown in Fig. 4, the rear end thereof will be formed tight or closed so as to confine the entrance of the air to the forward end. The inner casing may or may not be used with the modification shown in Fig. 4, but in case it is not the blades F are made of a size to fit the casing C.

M is a handle attached to casing C whereby the nozzle may be conveniently manipulated by the operator. In use the mouth of the nozzle is pressed against the cotton in the boll by the operator and the air suction draws all the free or loose fiber from the boll into the picking tube or cylinder G, the inturned teeth on the short tube K in the meantime engaging the cotton and loosening it up and carrying it around until it is dislodged and carried back into the picking tube or cylinder G by the air. In the event the teeth on tube K meet with an obstruction sufficient to retard or stop the rotary movement of the tube with the picking tube or cylinder G the pin L acts to reciprocate the tube and thus free the teeth from the obstruction. By reason of the rapid

and constant pulling on the fiber by the tube K while engaged therewith the same is so loosened and opened up that trash or dust drops out of it and the cotton is rendered more susceptible to the action of the air and easily passes through the picking tube or cylinder to the conveying pipe A. 70

Having thus described my invention what I claim as new and desire to secure by Letters Patent is:

1. A nozzle for a cotton picker, comprising a revolving conveyer tube; a relatively short freely revolving tube carried by one end of the first revolving tube; picker teeth attached to the short tube; and means connecting the two tubes to cause reciprocation of the shorter one when abnormal resistance is encountered by the said picker teeth while the longer tube revolves. 75

2. A nozzle for a cotton picker, comprising a revolving conveyer tube; a relatively short tube carried by one end of the first tube; picker teeth attached to the shorter tube; an inclined, continuous groove in one of the tubes; and means in the other tube engaging the said groove to cause reciprocation of the shorter tube when abnormal resistance is encountered by said picker teeth while the longer tube revolves. 80

3. A nozzle for a cotton picker, comprising a revolving conveyer tube; a relatively short tube carried by one end of the first tube; picker teeth attached to the shorter tube; an inclined, continuous groove in the shorter tube; and means on the first mentioned tube engaging the said groove to cause reciprocation of the shorter tube when abnormal resistance is encountered by said picker teeth while the longer tube revolves. 95

4. A nozzle for cotton picking apparatus, comprising a revolving tube having spirally arranged blades attached thereto; a fixed non-revolvle casing surrounding said tube and blades and spaced at one end from said tube to form an air port; a spider rigidly attached to the other end of the said casing; and a second non-revolvle casing open at one end and inclosing the first mentioned casing and fixedly secured in spaced relation thereto by the spider at its open end 100 and by the revolving tube at its other. 105

5. A nozzle for a cotton picker, comprising a revolving tube having spirally arranged blades attached thereto; a fixed non-revolvle casing inclosing part of the said tube and the blades and having a port at one end; a second non-rotating casing inclosing the first casing in spaced relation thereto and open at one end; a spider connecting the open end of the outer casing to 110 the closed end of the inner casing. 115

6. A nozzle for a cotton picker, comprising a revolving tube having spirally arranged blades attached thereto; air ports in the said tube adjacent the said blades; a fixed 120

non-revolvle casing having a bearing at one end for the tube and spaced from the tube at its other end; a second fixed non-revolvle casing open at one end and closed at the other end about the revolving tube encompassing the first mentioned casing and spaced therefrom to form an air passage; and a spider connecting the open end of the outer casing with the inner casing adjacent 5 to the bearing.

10. to said bearing.

7. A nozzle for a cotton picker, comprising a revolving tube having spirally arranged blades attached thereto; air ports in the said tube adjacent the said blades; a 15 fixed non-revolvle casing having a bearing at one end for the tube adjacent the said air

ports and spaced from the tube at its other end; a second fixed non-revolvle casing open at one end and closed at the other end about the revolving tube encompassing the first mentioned casing and spaced therefrom to form an air passage; and a spider connecting the open end of the outer casing with the inner casing adjacent the said bearing.

25

In testimony whereof, I affix my signature, in the presence of two witnesses.

ALBERT P. ALBERT.
